COMBINED MATCH BOX AND TRAY

Glen W. Hamilton, Kansas City, and Vinton H. Rowlett, St. Louis, Mo.

Application December 10, 1937, Serial No. 179,144

5 Claims. (Cl. 206—31)

This invention relates to improvements in combined match box and tray and has for its principal object the provision of a match box suitable for use as a match tray when partially opened and suspended from a nail on the wall.

Another object of the invention is the provision of a combined match box and tray having means for securing the parts in fixed relative relation when the device is being used as a tray.

With these, as well as other objects in view, the invention consists in the novel construction, arrangement and formation of parts, as will be more specifically described, claimed and illustrated in the accompanying drawing, forming a part of this application.

Figure 1 is a perspective view of a combined match box and tray, partly broken away to disclose certain features, embodying this invention.

Fig. 2 is a stretch-out of the body of the box shown in Fig. 1.

Fig. 3 is a central longitudinal sectional view of the box shown in solid lines in the closed portion and dotted lines in the open position when used as a tray.

Fig. 4 is a cross-sectional view taken on line IV—IV of Fig. 1.

Referring to the drawing in detail, wherein like reference characters designate similar parts throughout the several views, the numeral 10 generally designates the box body. As shown, the box body is of an elongated, substantially rectangular shape, and is formed of a single piece of fiber-board or similar material, shaped as shown in Fig. 2 and folded and secured together to present a receptacle suitable for holding matches, toothpicks, etc., as shown in Figs. 1, 3 and 4.

Referring to Fig. 2 showing the blank or stretch-out of the box body, it will be noted that the sheet of material 12 is slotted and scored to present a bottom 14, side walls 16, end walls 18 and 20, also flaps 22, which when positioned as shown in Fig. 1, produce a rectangular box. The flaps 22 are secured to the end walls 18 and 20 by paste, riveting or cementitious strips to secure the box in proper form. The scoring 24 makes it possible to accurately fold the parts without undue bending of the board.

The end wall 20 has an extension 26 having an outer portion 27 provided with oppositely disposed side wings 28 which are spaced apart from the flaps 22. The extension 26 is scored at 30 to facilitate proper folding. Referring to Figs. 1, 3 and 4 it will be observed that extension 26 normally closes the end portion of the box, while the wings 28 extend into the box and rest against the

respective side walls. When so positioned the material, such as matches filling the box, tend to hold the parts together. The outer portions of wings 28 are provided with outwardly projecting tongues 32 and notches 34; also a portion of each of the wings and the outer portion 27 of extension 26 are concaved to produce proper access to the tray when the same is in use.

The box cover 36 is an elongated, tubular member of rectangular cross-section, of a size suitable for slipping snugly over the box, with opposite open ends substantially registering with the respective ends thereof. This cover is of the type now in general use on match boxes and is made of a material similar to that used in making the box body. The cover consists of top 38, sides 40 and bottom 42. As shown in Fig. 4 the material is lapped at one side and secured together by paste or in any other suitable manner. The bottom 42 of the cover is provided with an opening 44 which is in longitudinal alignment with a similar opening 46 formed through the bottom 14 of the box body. When the box is closed, as shown in solid lines in Fig. 3, the openings 44 and 46 are out of register, however, when the box is arranged to form a tray, as shown in dotted lines in Fig. 3, then the openings will be in register to receive the head portion 48 of a supporting nail 50 which is secured in a vertical wall 52.

When the nail is thus positioned in the openings to support the box in a vertical position, it will be noted that the lower edge of the top 38 of the cover will extend into the notches 34 while the tongues 32 will be secured against outward movement by said top. The extension 26 and wings 28, when positioned as shown in dotted lines, with the cover raised, provide a tray 54 into which the matches roll by gravity. As the matches are taken from the tray others will move downwardly to take their place so that the box may be completely emptied without further manipulation of the box.

To open the box and form the tray, the cover is first moved beyond the edge of extension 26, which is then engaged and moved outwardly from the box and into the path of the cover top 38, which is now moved downwardly until the edge thereof rests in notches 34 with the tongues 32 resting against the inner side of cover top 38. When thus positioned the openings 44 and 46 will be in register so that the box may be placed in position on nail 50. So long as the nail is positioned in said holes, the box and cover are secured against relative movement with the cover 55.

top positioned in the notches 34 to hold the tray parts in fixed relation.

It will be noted that when the box is positioned to form a tray that the body portion 26 is in substantially planar relation with the end member 20 to form an extension whereby the tray bottom is extended beyond the body of the box while the outer portion 27 is positioned vertically to present a side wall for the tray. With the parts thus positioned, it is apparent that the operator will have easier access to the articles within the tray because they will be positioned on extension 26.

This device is inexpensive and could be discarded when emptied, however, it might be refilled and used for a long period of time, especially if made from durable material.

Many minor changes might be made in the construction of the parts without departing from the spirit of this invention.

Having thus described the invention, what is claimed as new and desired to be secured by Letters Patent is:

1. A combined match box and tray comprising a box body having a bottom, longitudinal side walls and end walls, one of said end walls having an angled extension with the inner portion thereof in planar relation with the adjacent end wall and with the outer portion thereof upwardly inclined thereto and provided with side wings, formed to lay against the respective side walls of the box, a tubular cover slidably mounted on said box body whereby the box may be closed; and a tongue formed at the outer extremity of each wing adapted to be positioned to contact the inner surface of the top wall of said cover when the parts are positioned to form a tray for the reception of matches from said box.

2. A combined match box and tray comprising a box body having a bottom, side walls and end walls, one of said end walls having an extension substantially the entire width thereof, said extension consisting of an inner portion adapted to be positioned in planar relation with the adjacent end wall and an outer portion adapted to be positioned at an angle to the inner extension portion; a wing at each side of the outer extension portions normally spaced apart from said adjacent box end and adapted to rest against the inner faces of the said side walls respectively; a tubular cover slidably mounted on said box body; and notches formed in the outer edge of each of said wings, said extension, wings and cover being adjustable to present an open tray with the edge of said cover positioned in said notches to secure the said parts in fixed relation.

3. A combined match box and tray comprising a box body having a bottom, longitudinal side

walls and end walls, one of said end walls having an extension including an inner portion in planar relation with said end wall and an outer portion angled upwardly therefrom and provided with side wings formed to respectively lay against the inner surfaces of said side walls; a tubular cover slidably mounted on said box body whereby the box may be closed; and a tongue formed at the outer extremity of each wing adapted to be positioned to contact the inside surface of the top of the partially opened cover to secure the extension in an extended position whereby a tray is formed to receive the matches from said box.

4. A combined match box and tray comprising a box body having a bottom having an opening formed therethrough, longitudinal side walls and end walls, one of said end walls having an extension with side wings adjacent its outer portion formed to lay against the respective side walls of the box, having an opening formed through the bottom thereof, the inner portion of said extension being adapted to be positioned in substantially planar relation with the adjacent end wall while the outer portion of the extension is positioned at an angle vertically thereto, a tubular cover slidably mounted on said box body whereby the box may be closed; and a tongue formed at the outer extremity of each wing adapted to be positioned to contact the inner surface of the top wall of said cover when the parts are positioned to form a tray for the reception of matches from said box, the openings in said box bottom and cover being in register, when the tray is formed, to receive the end portion of a nail therethrough to support the box.

5. A combined match box and tray comprising a box body having a bottom provided with an opening therethrough, and having side walls and end walls, one of said end walls having an extension substantially the entire width thereof and a portion thereof being adapted to be positioned in planar relation therewith while the outer portion thereof is extended upwardly at an angle thereto, a wing at each side of the upwardly extended portion of said extension positioned to lay against the inner surface of said side walls; a tubular cover slidably mounted on said box body and having an opening in the bottom side thereof adapted to register with the opening in the bottom of the box body; and notches formed in the outer extremity of each of said wings adapted to receive the edge portion of said cover, when the same is partially opened and the extension and wings are positioned to form a tray.
